UNITED STATES PATENT OFFICE.

ANDREW LANZ, OF PITTSBURGH, PENNSYLVANIA.

FUEL-FEEDING APPARATUS.

1,327,764.

Specification of Letters Patent. Patented Jan. 13, 1920.

Application filed February 24, 1919. Serial No. 278,967.

To all whom it may concern:

Be it known that I, ANDREW LANZ, a citizen of the United States, a resident of Pittsburgh, in the county of Allegheny and State 5 of Pennsylvania, have invented a new and useful Improvement in Fuel-Feeding Apparatus, and do hereby declare the following to be a full, clear, and exact description thereof.

10 My invention relates to apparatus for feeding fuel to furnaces.

The object of my invention is to provide a simple and efficient apparatus of this character in which the coal is evenly and uniformly distributed from a central point to the grates, the coal being lifted to a point above the grates and dropping by its own gravity onto the grates, whereby slack and fine coal can be economically employed to 20 produce a very hot fire, and all without the employment of manual labor.

To these ends my invention comprises the novel features hereinafter set forth and claimed.

25 In the accompanying drawing Figure 1 is a side elevation of a portion of a common form of brick-kiln showing my invention applied thereto; Fig. 2 is a sectional elevation; Fig. 3 is a sectional elevation taken at right angles to Fig. 2; Fig. 4 is a section on the line 4—4 Fig. 2.

In the drawing the numeral 2 designates a brick-kiln of a common type with the openings 3 formed at intervals provided 35 with sliding doors 4.

The fire chambers 5 are provided with the grates 6. Between each pair of fire chambers and elevated above same is the deflector 7, built up of masonry and provided with 40 the sloping faces 8.

Formed within the deflector 7 is the cylindrical chamber 9 lined with the casing 10, having a bottom portion 11. The discharge opening 9^a is surrounded by the collar 9^b for 45 the purpose more fully hereinafter set forth.

Below the chamber 9 is the chamber 12. A vertical shaft 13 is journaled in suitable bearings 14, and the upper portion of said shaft carries the spiral conveyer 15.

50 At the lower end of the shaft 13 is the ratchet-wheel 16. An arm 17 is mounted loosely on the shaft 13, and said arm carries the pawl 18 adapted to engage the ratchet-wheel 16. The outer end of the arm 17 is connected to a rod 19 which is adapted to be reciprocated by any suitable power

means. By the above construction it will be apparent that when the rod 19 is reciprocated, the arm 17 will be moved to impart an intermittent rotary movement of the 60 shaft 13 through the ratchet and pawl. It is apparent that a properly regulated continuous movement of the conveyer may be employed.

A distributor 20 is arranged in the upper 65 end of the cylindrical chamber 9, so as to properly distribute the fuel in the manner more fully hereinafter set forth. The lower portion of said distributor may be formed of cast iron as said lower portion is not exposed 70 directly to the heat of the furnace, but the upper portion 20' is composed of fire-brick to withstand the heat to which it is exposed.

A hopper 21 is provided for delivering 75 fuel to the chamber 9, said hopper being arranged on the outside of the furnace and communicating with said chamber by the opening 22.

When my invention is in operation the 80 coal in the form of slack and fine coal is delivered to the hopper 21, and passes thence into the chamber 9. Power having been applied to reciprocate the rod 19, an intermittent rotary movement is imparted to the 85 shaft 13 and the spiral conveyer carried thereby, whereby the coal contained within the chamber 9 is raised and discharged from the upper end of said chamber, the distributor 20 acting to divide the coal evenly to 90 both sides of the deflector 7. The coal as it is discharged from the upper end of the chamber 9 passes down the inclined faces 8 of the deflector, and is delivered to the grates 6. By having the collar 9^b around the opening 9^a, the coal is distributed evenly along 95 the inclined faces 8, and the heaping of the coal at any one point on the grates is avoided.

The coal delivered in this way is fed in 100 uniform quantities to the grate, and consequently the fire is kept at a substantially uniform degree of heat. The heavier particles of coal will fall first onto the grates, and the finer material in the form of 105 powder will be practically ignited before it reaches the grates, and a very hot fire will thus result.

By my invention without the aid of 110 manual labor, the fires are kept up and fed automatically, the only requirement being to see that the supply hoppers are filled with

coal, so that I dispense with the labor usually required in furnaces of this character for shoveling the fuel through the openings into the grates. The opening of the doors each time the fuel is introduced in this manner resulting in a loss of heat and a reduction of the temperature of the kiln. By my invention the raising of the doors is not necessary except for purposes of cleaning or repairs.

10 What I claim is:

1. In fuel feeding apparatus for furnaces, the combination with a pair of grates, of a deflector between and elevated above the 15 grates and independent thereof, and having a fuel passage formed therein, and means for delivering fuel from the upper end of said passage onto said deflector.

2. In fuel feeding apparatus for furnaces, 20 the combination with a pair of grates, of a wall separating the grates and rising above them, and having a fuel passage formed therein, and means for delivering fuel from the passage at the upper end of said wall 25 onto said grates.

3. In fuel feeding apparatus for furnaces, the combination with a pair of grates, of a partition between and rising above said 30 grates, having downwardly inclined side faces, and having a fuel passage therein, and means for delivering the fuel from the upper end of said passage onto said faces.

4. In fuel feeding apparatus for furnaces, the combination with a pair of grates, of a 35 partition wall between and rising above said grates, having downwardly inclined side faces, and having a fuel passage formed therein, a collar surrounding the outlet of said passage, and means for delivering the

fuel from the upper end of said passage 40 onto said faces.

5. In fuel feeding apparatus for furnaces, the combination with a pair of grates, of a deflector wall between and rising above said 45 grates, having a fuel passage formed therein, and a spiral conveyer arranged in said fuel passage.

6. In fuel feeding apparatus for furnaces, the combination with a pair of grates, of a deflector wall between and rising above said 50 grates, having downwardly inclined side faces, a fuel passage formed in said wall, a spiral conveyer arranged in said passage, and a distributor at the upper end of said passage.

7. In fuel feeding apparatus for furnaces, the combination with a pair of grates, of a deflector wall between and rising above said 60 grates, having downwardly inclined side faces, a fuel passage formed in said wall, a spiral conveyer in said passage, and means for imparting an intermittent movement to said conveyer.

8. In fuel feeding apparatus for furnaces, the combination with a pair of grates, of a 65 deflector wall between and rising above said grates, having downwardly inclined side faces, a fuel passage formed in said wall, a spiral conveyer in said fuel passage, and a supply hopper contained in said fuel 70 passage.

In testimony whereof I, the said ANDREW LANZ, have hereunto set my hand.

ANDREW LANZ.
